Primary Examiner — Mimosa De(74) *Attorney, Agent, or Firm* — McAndrews Held &
Malloy, Ltd.(57) **CLAIM**The ornamental design for a storage cabinet trim piece, as
shown and described.**DESCRIPTION**FIG. 1 is a top-front perspective view of a storage cabinet
trim piece showing my new design;

FIG. 2 is a front elevation view thereof;

FIG. 3 is a rear elevation thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is an enlarged cut-away view of FIG. 1, showing a
drawer on which the storage cabinet trim piece is installed,
the drawer being shown separately for clarity of illustration;
FIG. 9 is an enlarged view of the portion 9 encircled in FIG.
1;FIG. 10 is an enlarged view of the portion 10 encircled in
FIG. 4;FIG. 11 is an enlarged view of the portion 11 encircled in
FIG. 5;FIG. 12 is an enlarged view of the portion 12 encircled in
FIG. 8; and,FIG. 13 is an enlarged view of the portion 13 encircled in
FIG. 7.The dashed broken lines in the figures illustrate portions of
the storage cabinet trim piece that form no part of the
claimed design. the storage cabinet trim piece is shown with
a symbolic break in its length. The appearance of any portion
of the storage cabinet trim piece between the jagged break
lines forms no part of the claimed design. The dot-dash
broken lines in the drawings encircle portions of the claimed
design that are illustrated in enlargements and form no part
of the claimed design.**1 Claim, 10 Drawing Sheets**(58) **Field of Classification Search**
